CLAIM

The ornamental design for an automatic-transfer-switch cover assembly as shown and described.

DESCRIPTION

FIG. 1 is a perspective view taken from the top, front, left side of an automatic-transfer-switch cover assembly, according to our new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The rear surfaces of the claimed automatic transfer switch cover assembly are not shown in the drawings and form no part of the claimed design. The broken line portion of the figure drawings is included to show unclaimed subject matter only and forms no part of the claimed design.
